[57] **CLAIM**

The ornamental design for a combined collapsible chair and container, as shown and described.

DESCRIPTION

FIG. 1 is a perspective view of a combined collapsible chair and container showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view, the opposite side being a mirror image thereof;

FIG. 7 is a perspective view thereof, with the container cover in a raised condition; and

FIG. 8 is a perspective view thereof, with the seat back in the operational condition.

FIG. 1

FIG. 2

FIG. 3

FIG. 4
